Inventor

Robert J. Staph

By his Attorney

Merchants & Kegor

UNITED STATES PATENT OFFICE.

ROBERT J. STAFF, OF NORTHFIELD, MINNESOTA.

RAZOR-BLADE HOLDER.

Application filed May 22, 1926. Serial No. 110,924.

My invention has for its object to provide an extremely simple and highly efficient razor blade holder, and to this end it consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the invention with a razor blade applied thereto;

Fig. 2 is a side elevation of the invention with one of the springs released and the razor blade removed;

Fig. 3 is a view partly in side elevation and partly in longitudinal central section showing a razor blade mounted in the opposite spring from that shown in Fig. 1;

Fig. 4 is a fragmentary detail view, on an enlarged scale, with some parts sectioned, of the razor blade holder with both springs compressed; and

Fig. 5 is a transverse section on the line 5—5 of Fig. 4.

The improved holder comprises a pair of sear springs 6 and 7 and a slidable sleeve-like handle 8. The sear springs 6 and 7 are turned toward each other in longitudinal adjustment and have one member of each spring integrally formed. Both sear springs 6 and 7 are formed from a single half-round spring rod which, when the members of said springs are compressed, are round in cross section. The handle 8 is mounted on the springs 6 and 7 for longitudinal sliding movement from one spring to the other for holding the members thereof compressed or for telescopic movement onto the free members of both springs for simultaneously holding their loose members compressed.

It will be noted that the free member of the spring 6 is somewhat shorter than the free member of the spring 7 and that the space between its members is less than that between the members of the spring 7. The spring 6 is adapted to hold a relatively short and thin razor blade α , as shown in Fig. 1, and the spring 7 is adapted to hold a relatively long and thick razor blade γ , as shown in Fig. 3. The outer ends of the springs 6 and 7 are upset at 9 to afford stops to prevent the handle 8 from being removed from the springs.

In applying a razor blade to the holder

the handle 8 is slid completely onto one of the springs to release the free member of the other spring, as shown in Fig. 2. The razor blade is then inserted longitudinally between the members of the released spring until its outer end portion binds between said members. The free member of said spring is then sprung onto the other member thereof and the handle 8 telescoped over the inner end of said free member to hold the razor blade clamped between the members of the spring, as shown in Figs. 1 and 3. The tension of the free members of the springs 6 and 7 is such as to securely hold the handle 8 against endwise sliding movement on the springs or rotation thereon.

With the razor blade held by the improved holder the same may be stropped as with an ordinary straight razor and the blade reversed each time it is brought into engagement with the strop by turning the handle 8 between the fingers and thumb of the operator. The diameters of the springs 6 and 7, when compressed, are such that when stropping a razor blade the respective spring will lie on the strop and hold the edge of the blade in a manner to produce a long bevel on the edge of the razor blade which is highly important in producing a keen cutting edge.

What I claim is:

1. A blade holder comprising a longitudinally extended member having clamping arms at its opposite ends projecting inwardly toward each other, and a single sleeve mounted upon and about said member and freely movable in opposite directions thereon to slide over and clamp both or either of said arms to said member.

2. A razor blade holder comprising two sear springs turned toward each other in longitudinal alignment and having two of these members integrally formed, a sleeve-like member mounted on said spring and movable from one sear spring to the other to hold the free members thereof compressed while the free member of the other spring is released, said sleeve-like member being arranged, when holding the free member of one spring compressed, to be slid over the inner end of the free member of the other spring to hold the same compressed to clamp a razor blade between the member of the respective spring.

3. The structure defined in claim 2 in which the outer ends of the springs are

upset to prevent the removal of the sleeve-like member from the springs.

4. The structure defined in claim 2 in which the members of one spring, when compressed, are spaced differently from the members of the other spring when compressed.

5. The structure defined in claim 2 in which the free member of one spring is

longer than the free member of the other 10 spring.

6. The structure defined in claim 2 in which the springs are formed from a single half-round spring rod which, when the members of each spring are compressed, are 15 round in cross section.

In testimony whereof I affix my signature.

ROBERT J. STAPF.
